US0D1045064S

(12) **United States Design Patent** (10) Patent No.: **US D1,045,064 S**
Glenn, Jr. (45) Date of Patent: ** Oct. 1, 2024

(54) **SINGLE-DOSE DISSOLVABLE PERSONAL CARE UNIT**

(71) Applicant: **The Procter & Gamble Company**, Cincinnati, OH (US)

(72) Inventor: **Robert Wayne Glenn, Jr.**, Singapore (SG)

(73) Assignee: **The Procter & Gamble Company**, Cincinnati, OH (US)

(**) Term: **15 Years**

(21) Appl. No.: **29/795,025**

(22) Filed: **Jun. 16, 2021**

(30) **Foreign Application Priority Data**

Dec. 17, 2020 (WO) WIPO100299

(51) **LOC (14) Cl.** **24-01**

(52) **U.S. Cl.**

USPC **D24/102**

(58) **Field of Classification Search**

USPC D24/100-104; D1/115, 122

CPC A61K 9/4808; A23K 50/40

See application file for complete search history.

(57) **CLAIM**

The ornamental design for single-dose dissolvable personal care unit, as shown and described.

DESCRIPTION

FIG. 1 is a perspective view of a first embodiment of single-dose dissolvable personal care unit embodying our new design;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

1 Claim, 7 Drawing Sheets
